UNITED STATES PATENT OFFICE.

THOMAS J. GREENE AND PETER W. BURKE, OF BREMERTON, WASHINGTON.

PNEUMATIC-HAMMER-OILING DEVICE.

1,388,459.

Specification of Letters Patent. Patented Aug. 23, 1921.

Application filed February 18, 1920. Serial No. 359,594.

To all whom it may concern:

Be it known that we, THOMAS J. GREENE and PETER W. BURKE, citizens of the United States, residing at Bremerton, in the county 5 of Kitsap, State of Washington, have invented a new and useful Pneumatic-Hammer-Oiling Device; and we do hereby declare the following to be a full, clear and exact description of the invention, such as 10 will enable others skilled in the art to which it appertains to make and use the same.

The invention relates to pneumatic hammers and has for its object to provide an 15 oiling device for this type of hammer wherein oil will be fed to the hammer working parts through the air passage, while the hammer is in operation, and the feeding of oil automatically stopped when the hammer is not in operation. It has been found that 20 by supplying a constant supply of oil to the hammer during operation that the hammer may be used under all conditions of weather without the development of various troubles 25 incident to weather conditions and constant use.

A further object is to provide an oil receptacle interposed between the air intake port of the hammer and the air hose. Said receptacle comprising a member having an 30 oil chamber therein, which oil chamber has passing therethrough a tubular member for the passage of air to the hammer. The wall of the tubular member being provided with apertures in communication with the chamber 35 of the oil chamber so that as air is forced through the tubular member, said air will enter the oil chamber and force oil through one of the apertures of the tubular member into the air passage where it will be conveyed 40 to the working parts of the hammer. Oil being prevented from flowing into the air passage when the air is cut off by the pressure within the hose line.

With the above and other objects in view 45 the invention resides in the combination and arrangement of parts as hereinafter set forth, shown in the drawings, described and claimed, it being understood that changes in the precise embodiment of the invention may 50 be made within the scope of what is claimed without departing from the spirit of the invention.

In the drawings:—

Figure 1 is a side elevation of a conventional 55 form of pneumatic hammer, showing the oil feed cup attached thereto.

Fig. 2 is a plan view of the oil feed cup.

Fig. 3 is a longitudinal sectional view through the oil feed cup.

Fig. 4 is a sectional view through the feed 60 cup taken on line 4—4 of Fig. 2.

Fig. 5 is an enlarged detailed sectional view of the oil feed cup tubular member.

Referring to the drawings, the numeral 1 designates a conventional form of pneumatic 65 hammer and 2 the handle thereof, said handle being provided with a conventional form of finger engaging lever 3 for controlling the passage of air to the hammer. Threaded in the intake end 4 of the handle 2 is a 70 globular member 5, which globular member is provided with a chamber 6 for the reception of oil which may be placed therein through the threaded aperture 7 which is normally closed by a plug 8. Globular 75 member 5 is provided with a threaded extension 9 to which extension a conventional form of internally threaded hose pipe coupling 10 is secured. Extending longitudinally through the chamber 6 of the globular member is a tube 11, which tube has 80 one of its ends disposed in an annular recess 12 in one end of the globular member while the other end of the tube 11 is disposed as at 13 in the threaded extension 9. The 85 chamber 14 of the tubular member 11 forms an air passage whereby air is passed from the hose 15 to the air passage 16 in the threaded portion 17, which threads into the intake end 4 of the hammer handle.

Disposed in the hose coupling 10 and held in position by means of a shoulder 18 in the interior of said coupling is a screen 19, which screen, when the coupling 10 is threaded on the threaded extension 9, is jammed against 95 the end of the threaded extension 9 and also against the end of the tube 11, thereby not only holding the screen 19 in position but also holding the other end of the tubular member 11 in the annular recess 12 so that 100 the air from the hose line will pass through the chamber 14 of the tubular member 11 and air passage 16 of the extension 17 to the intake of the hammer.

Tubular member 11 is provided with apertures 20 and 21. Aperture 21 being in communication with the oil chamber 6 adjacent its lower end 22 and forms a passage through which oil passes from the oil chamber 6 to the air passage 14, from which passage the 110 oil passes to the working parts of the pneumatic hammer. While the hammer is in

operation the oil will be forced through the passage 21 by the air which passes through the passage 20, into the oil chamber 6. However, when the hammer is not in use and the 5 air pressure is within the pipe line and air passages 14 and 16 the pressure will be uniform and consequently the flow of oil through the passage 21 will be prevented by said pressure.

10 From the above it will be seen that an oil feed attachment is provided for pneumatic hammers which attachment will automatically feed oil to the air passage and to the working parts of the pneumatic hammer 15 while the same is in use. It will also be seen that when the hammer is not in use that the feeding of oil from the oil chamber 21 will be automatically cut off.

The invention having been set forth what 20 is claimed as new and useful is:—

An oiling device for pneumatic hammers comprising a body having an oil receptacle therein, said body member having its ends reduced and provided with axially aligned 25 air passages, one of said reduced portions of the body member being threaded, a tubular member extending through the oil receptacle of the body member and having one of its ends reduced and disposed within a

counterbore adjacent one end of the body 30 member and with the passage of the tube in axial alignment with the passage of the reduced portion of the body member, the other enlarged end of the tubular member being disposed in the passage of the 35 threaded reduced end of the body member, a screen engaging the end of the reduced threaded end of the body member and the enlarged end of the tubular member, a shouldered member threaded on the reduced 40 threaded end of the body member and forming means for maintaining the tubular member and the screen in position, said screen preventing displacement of the tubular member and passages of communication between 45 the air passage of the tube and the oil receptacle whereby air will enter the oil receptacle and force air into the air passage of the tube.

In testimony whereof we have signed our 50 names to this specification in the presence of two subscribing witnesses.
